P.C.(57) **CLAIM**

The ornamental design for a combined bib and burping shield, as shown and described.

DESCRIPTION

FIG. 1 is a first perspective view of a combined bib and burping shield in full lines.

FIG. 2 is a front elevational view of the combined bib and burping shield.

FIG. 3 is a rear elevational view thereof.

FIG. 4 is a right side elevational view thereof.

FIG. 5 is a left side elevational view thereof.

FIG. 6 is a top plan view thereof; and,

FIG. 7 is a bottom plan view thereof.

The broken lines showing in FIGS. 1-3 are for the purpose of illustrating the environment of the article only and form no part of the claimed design.
